UNITED STATES PATENT OFFICE.

THOMAS P. SCULLY, OF ROME, NEW YORK.

DETACHABLE HORSESHOE.

No. 893,201.

Specification of Letters Patent.

Patented July 14, 1908.

Application filed August 7, 1907. Serial No. 387,483.

To all whom it may concern:

Be it known that I, THOMAS P. SCULLY, a citizen of the United States, and a resident of Rome, in the county of Oneida and State of New York, have invented a new and Improved Detachable Horseshoe, of which the following is a full, clear, and exact description.

The object of the invention is to provide a new and improved detachable horse shoe, which is simple and durable in construction, and arranged to preserve the animal's hoof to the fullest extent, and to permit of conveniently placing the wearing member in position on a permanent member or for removing the wearing member of the horse shoe when the calks are dull or worn out or broken, to permit of removing the calks and replacing the wearing member.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a perspective view of the improvement as applied, the wearing member being removed; Fig. 2 is a longitudinal sectional elevation of the improvement as applied; Fig. 3 is a perspective view of the wearing member, and Fig. 4 is a transverse section of the improvement on the line 4—4 of Fig. 2.

The detachable horse shoe consists essentially of two superimposed members A and B, simulating an ordinary horse shoe in both form and effect, the upper or permanent member A being secured in the usual manner by nails C, to the under side of the animal's hoof D, while the lower or wearing member B is preferably provided at the underside with a toe calk E and heel calks F. The lower member B is removably attached to the upper member A by interlocking devices located at the toe and heel portions, and for this purpose the toe of the upper, permanent member A is provided with an aperture G adapted to be engaged by a hook H secured or formed on the top of the wearing member B at the toe portion thereof. The heel portions of the upper, permanent member A are provided with apertures I and longitudinally extending slots I' leading from the terminals of the

heel portions to a distance forward beyond the apertures I, to intersect the same, as plainly indicated in Fig. 1. By the arrangement described the heel portions of the permanent member A are split lengthwise, to form retaining devices for studs J, secured or formed on the top of the heel portions of the lower or wearing member B. The studs J are headed and the under sides of the apertures I are countersunk, to permit the heads of the studs J to readily engage the apertures I and to pass through the same until the heads of the studs rest with their undersides on the top surfaces of the heel portions of the upper permanent member A, as plainly indicated in Fig. 4.

By reference to Figs. 1 and 2, it will be seen that the heel portions of the members A and B extend beyond the animal's hoof, so that the heads of the studs J do not interfere with the animal's hoof D. The toe of the animal's hoof D is provided with a recess D', to readily accommodate the top of the hook H when the latter is engaged with the aperture G, as indicated in Fig. 2.

It is understood that by the arrangement described the member A is permanently secured to the hoof D, while the member B is removably attached to the permanent member A, and hence when the wearing member B is worn out or broken it can be readily removed from the permanent member A and replaced by a new one.

In order to place the wearing member B in position on the permanent member A, the operator first engages the hook H with the aperture G and then swings the wearing member B upward and forces the studs J through the apertures I, it being understood that the split members of the heel portions will readily yield owing to their own resiliency, and as soon as the studs have reached the upper surfaces of the heel portions then the split members are closed by their own resiliency, to securely hold the studs J in place. The member A is practically permanently attached to the animal's hoof and needs only removal at long intervals, that is, when the hoof overgrows the said permanent member. The wearing member B can be readily removed by first prying the split members of the heel portions open with a suitable tool to allow of disengaging the studs J from the apertures I, after which the member B is swung down to disengage the hook H from the aperture G. The calks of the wearing member

B can now be sharpened or replaced by new ones, after which the wearing member B is replaced, so that the expense to the owner of the animal is reduced to a minimum. In a like manner an entirely new wearing member B can be placed in position on the permanent member A.

Having thus described my invention, I claim as new and desire to secure by Letters Patent:

1. A horseshoe, comprising superimposed members, of which the upper member is for attachment to the under side of the animal's hoof and is provided at the toe with a toe aperture, the heel portions of the said upper member being formed into spring members, the lower member having a hook at the toe for engagement with the said toe aperture and the heel portions of the said lower member having studs for engagement with the said spring members.

2. A horseshoe, comprising superimposed members simulating an ordinary horse shoe, the upper member being for permanent attachment to the under side of the animal's hoof, the heel portions and the toe portions of the said members having interlocking means for removably securing the lower member in position on the upper member, the interlocking means at the toe portions consisting of a hook on one member engaging an aperture in the other member, and the interlocking means at the heel portions consisting of studs on one member engaging spring retaining-means on the other member.

3. A horseshoe, comprising superimposed members of which the upper member is for attachment to the underside of the animal's hoof and is provided at the toe with a toe aperture, the heel portions of the said upper member being provided with vertical apertures and longitudinal slots, said slots leading from the terminals of the heel portions and intersecting the apertures, the said lower member having a hook at the toe for engagement with the said toe aperture, and

the heel portions of the said lower member having studs for engagement with the said heel apertures.

4. A horseshoe, comprising superimposed members, of which the upper member is for attachment to the under side of the animal's hoof, and is provided at the toe with a toe aperture, the heel portions of the said upper member being provided with vertical apertures and longitudinal slots, said slots leading from the terminals of the heel portions and intersecting the apertures, the said lower member having a hook at the toe for engagement with the said toe aperture, and the heel portions of the said lower member having studs for engagement with the said heel apertures, the latter being countersunk at the bottom for the ready entrance of the heads of the said studs.

5. A horseshoe, comprising an upper member adapted to be secured to the animal's hoof and provided at its heel portions with spring jaws, a lower member having at its heel portions headed studs adapted to be engaged by the jaws of the upper member, and means for detachably securing the toe portions of the members together.

6. A horseshoe, comprising an upper member adapted to be secured to the animal's hoof and provided at its heel portions with apertures and longitudinal slots, said slots leading from the terminals of said heel portions and intersecting the apertures thereof, a lower member provided on its upper face at the heel portions with headed studs adapted to enter the apertures of the upper member, and means for detachably securing the toe portions of the members together.

In testimony whereof I have signed my name to this specification in the presence of two subscribing witnesses.

THOS. P. SCULLY.
